UNITED STATES PATENT OFFICE.

CLARENCE W. MOORE, OF ROSLYN, PENNSYLVANIA, ASSIGNOR TO ELECTRO DENTAL MANUFACTURING COMPANY, OF PHILADELPHIA, PENNSYLVANIA, A CORPORATION OF PENNSYLVANIA.

ELEVATING MECHANISM.

Application filed January 27, 1926. Serial No. 84,135.

My invention relates to elevating mechanism and it has particular application to such mechanisms as are applicable to adjustable dental, surgical and barber chairs.

5 One object of my invention is to provide mechanism of the character described, whereby a chair seat may be moved into a lower position than has heretofore been considered practicable and the range of movement of the chair simultaneously increased.

Another object of my invention is to provide chair elevating mechanism that shall be simple in design and construction, to facilitate assembly of parts in group of sub-assemblies, highly efficient in operation, and characterized by the substantial absence of noise and vibration.

A further object of my invention is to provide apparatus comprising a sectional folding chair post, a movable support therefor and means for exerting a thrust on said post over substantially the full length thereof.

Other objects and applications of my invention, as well as details of construction and operation, whereby my invention may be practiced, will be apparent more fully hereinafter, when taken in connection with the accompanying drawings, wherein

30 Fig. 1 is a side elevational view, partially in vertical section, of the elevating mechanism embodying my invention with the chair seat in its highest position, the sectional plane being on the line I—I of Fig. 3.

35 Fig. 2 is a similar view but illustrating the disposition of the elevating mechanism for the lowest position of the chair seat;

Fig. 3 is a top plan view of the structure of Fig. 2;

40 Fig. 4 is a vertical sectional view taken on the line IV—IV of Fig. 3;

Fig. 5 is a transverse sectional view taken on the line V—V of Fig. 4; and

45 Fig. 6 is a horizontal sectional view taken on the line VI—VI of Fig. 4.

Referring to the embodiment of my invention shown in the drawing, broadly speaking, a chair seat 1 is mounted on an upper end 2 of a folding sectional rack 3 which may be actuated by a motor 4 through

a reduction gear-wheel mechanism 5. The folding rack or chair post 3 may be slidably mounted on an upper dovetail guide 6 of a floating member 7, a lower dovetail guide 8 of which engages a stationary dovetail guide 9 of a casting 10 that is vertically positioned on a base plate 11.

The floating member 7 comprises a central wall section 12 having opposite sides 13 and 14 and edges 15 and 16. The lower dovetail guide or slide 8 may be formed by bending transversely, as shown in Fig. 6, the lower portions of the side edges 15 and 16, to form side flanges 17 and 18. The flange 18 may be apertured to receive a plurality of adjusting screws 19 for engagement with a gib 21. The gib 21 may be rigidly clamped to the wall section 12 in the desired adjusted position by means of bolts 22.

As shown in Fig. 6, the dovetail slide or guide 9 fits between the side flange 17, the gib 21 and the side 13, and it may be extended vertically sufficiently to guide the floating member 7 over its desired range of travel, all as will presently appear. The maximum upper position of the floating member 7 is determined, as shown in Fig. 1, by a pair of lugs 23 and 24 which are respectively mounted on the supporting casting 10 and the side flange 17. The lower position of the floating member 7 is as illustrated in Figs. 2, 3, 4 and 5.

The upper dovetail slide or guide 6 may be formed as in the lower guide 8 but on the opposite side 14 of the central wall section 12 by transversely bending the upper portions of the side edges 15 and 16, and it also is provided with a gib 25 and associated adjusting screws and clamping bolt 26 and 27, respectively.

The folding chair post 3 is provided with an upper section 28 having one side 29 in the form of a dovetail adapted to fit the upper dovetail slide 6. The side 29 is also provided with a slot 31 which receives one end 32 of an adjustable bolt 33 supported by the central wall section 12 at the upper end thereof, whereby the chair post 3 may have a lost-motion connection to the floating member 7. The length of the slot 31 is 100

sufficient to permit the desired independent movement of the chair post 3 and thereafter the simultaneous movement of the chair post 3 and the floating member 7 for reasons as will appear more fully hereinafter.

Another side 34 of the upper chair-post section 28 is provided with teeth constituting a rack 35. A lower end 36 of the upper section 28 is recessed as shown in Figs. 4 and 5 to receive an upper end 37 of a lower folding section 38 of the chair post 3. A pivot pin 39 serves to swingingly support the lower rack section 38 in position. A side 40 of the lower section 38 is also provided with teeth constituting a rack 41 which is in alignment with the upper rack section 35. The lower post section 38 is of reduced thickness with respect to the upper section 28 and it is provided with a shoe 42 on its underside 43 which slides over the adjacent portion of the side 14 as the chair post 3 moves relative to the floating member 7. The shoe 42 further prevents a swinging movement of the lower rack section 38 toward the side 14 under conditions of operation, hereinafter set forth.

The reduction gear-wheel mechanism 5 between the driving motor 4 and the folding chair post 3 includes a driving pinion 44, which is positioned to engage successively the rack section 35 and 41 of the upper and lower chair-post sections 28 and 38. As shown particularly in Fig. 5, the driving pinion 44 may be mounted on a horizontal shaft 45 which is journaled in bearings 46 and 47 formed in a vertically extending casting 48 supported on the base plate 11. Vibration of the adjacent upper ends 49 and 51 of the two castings 10 and 48 may be minimized by a pair of bolts 52 positioned as illustrated in Fig. 3.

A gear-wheel 53 is mounted on one end of the shaft 45 and it engages a gear-wheel 54 which is mounted on a second horizontal shaft 55 journaled in bearings 56 and 57 also formed in the casting 48. A worm wheel 58 is mounted on one end of the shaft 55 and engages a worm 59 mounted on a shaft 61 which is connected to the driving motor 4 through a flexible coupling 62. The worm-and-wheel 58-59 may be positioned in a recess 63 in the casting 48 and further protected by means of a cover plate (not shown). The advantage of positioning the worm-and-wheel 58-59 in immediate proximity to the driving motor 4 is the decrease in the number of high speed parts and therefore the substantial elimination of noise and vibration.

As illustrated in Figs. 4 and 5, the base plate 11 is provided with a recess 64 for the lower rack section 38 when the chair post 3 is in its lower position. Movement of the lower post section 38 to and from the folded po-

sition may be facilitated by means of an anti-friction roller 65 which is mounted on an outer free end 66 of said lower section 38. The base of the recess 64 is formed to provide a lower track 67. A complementary upper track 68 may be formed by means of a rib 69 which is formed on the casting 48, as shown in Fig. 5. The upper track 68 may be extended into a vertical section 71 by means of a plate 72 that is secured by bolts 73 to lugs 74 of the casting 48. The vertical section 71 of the track in co-operation with the anti-friction roller 65 serves to prevent a swinging movement of the lower post section 38 away from the floating member 7 when said lower portion 38 is engaged by the driving pinion 44, all as will presently appear.

Assuming the several parts to be in the position illustrated in Figs. 2 to 6, inclusive, the operation of the motor 4 causes the turning of the driving pinion 44 and hence the vertical movement of the upper rack section 28 of the chair post 3. The upper rack section 28 is guided during this movement by the upper dovetail slide 6 of the floating member 7. The lower rack section 38 is guided at this time by the anti-friction roller 65 and the tracks 67 and 68.

When the anti-friction roller 65 has been moved around to the dot-and-dash line position shown in Fig. 1, the driving pinion 44 has actuated the upper rack section 28 vertically a distance sufficient to cause the lug 32 of the lost-motion connection to engage the lower end of the slot 31, so that a further movement of the chair post 3 causes also a movement of the floating member 7. At this time, the driving pinion 44 moves from engagement with the rack 35 of the upper post section 28 into engagement with the rack 41 of the lower section 38. The line of action of the pinion thrust with respect to the pivot pin 39 is such that the lower post section 38 tends to swing away from the floating member 7, but this is prevented by the anti-friction roller 65 bearing against the vertical track section 71.

The continued vertical movement of the chair post 3, however, causes the line of action of the pinion thrust to move to the opposite side of the pivot pin 39 with the result that said lower post section 38 now tends to swing toward the floating member 7, but this is prevented by the shoe 42. Thus undesirable swinging movements of the lower rack section 38 are prevented. The vertical movement of the chair post 3 under the action of the driving pinion 44 may be continued until the lug 24 of the guiding member 7 moves into proximity to the lug 23 of the guiding support 10, whereupon the driving motor 4 may be de-energized by trip mechanism (not shown). The parts are now in the position illustrated in Fig. 1.

When the driving motor 4 is reversed, the

cycle of operations just described is reversed, the chair post 3 moving first downwardly simultaneously with the floating member 7 and thereafter independently thereof until the parts again assume the position shown in Figs. 4 and 5.

Should the gib 25 be so adjusted that the friction between the floating member 7 and the upper rack section 28 be greater than a desired value, then the operation of the driving pinion 44, when the parts are in the position illustrated in Figs. 4 and 5, causes the floating member 7 to move vertically simultaneously with the chair post section 28. In order that the lower rack section 38 may be prevented from swinging toward the floating member 7 under such conditions, a lug 75 is provided on the lower end of the central wall section 12, so that it may engage the adjacent side 43 of the lower rack section 38 and guide the same as it moves vertically until the shoe 42 moves into contact with the side 14 of the floating member 7. The lug 75 is so positioned relative to the shoe 42 and the anti-friction wheel 65 as to be out of the path of travel of the same.

While I have shown only one embodiment of my invention, for the purpose of describing the same and illustrating its principles of construction and operation, it is apparent that various changes and modifications may be made therein without departing from the spirit of my invention and I desire therefore that only such limitations shall be imposed thereon as are indicated in the appended claims or as are demanded by the prior art.

I claim:

1. Chair elevating mechanism comprising a sectional chair post movable into a folded position and an extended position, floating guiding means for said post operatively associated with at least one of said sections, said post sections being provided with teeth constituting a rack, and a driving pinion in engagement with one section when said post is in its folded position and another section when said post is in its extended position.

2. A post having one end adapted to engage a chair seat and provided with a hinged section at the other end, a floating guide for said post having a lost-motion connection therewith, and a guide for said first-mentioned guide, said hinged section under certain operating conditions being movable into a position angularly disposed with respect to the remaining portion of said post.

3. Apparatus of the class described comprising a sectional chair post having a lower position wherein the sections are disposed in angular relation, means for initially exerting a thrust on one section and thereafter on the other section, means for guiding said first-mentioned section as it moves under the action of said thrust, said second-mentioned

means serving to support said second-mentioned section as the thrust is exerted thereon, and means for guiding said first-mentioned guiding means as it is actuated by said chair post.

4. A chair post having a predetermined path of travel, said chair post having a hinged section movable into an angular position when said chair post approaches one end of its path of travel, a slide for said chair post adapted to serve as a guide for said hinged section when said chair post approaches the opposite end of its path of travel, and a slide for said first-mentioned slide.

5. Apparatus of the character described comprising a chair post having a lower hinged section movable into an angular position when said post is at one end of its path of travel, a slide for said chair post having a lost-motion connection therewith, means for actuating said chair post, said hinged section being provided with means for guiding the same as it moves from said folded position, and a slide for said first-mentioned slide.

6. A chair post having a lower hinged section movable into an angular position when said post is at one end of its path of travel, a slide for said chair post having a lost-motion connection therewith, means for actuating said chair post, said hinged section being provided with means for guiding the same as it moves from said folded position, and a slide for said first-mentioned slide, said hinged section being guided by said first-mentioned slide during a predetermined portion of its movement.

7. A member provided with a slide at one end, a sectional folding chair post, of which one section has a lost-motion connection with said slide, the other section being guided by the opposite end of said slide when said chair post is in a predetermined position, a plurality of teeth formed on said chair post, and a pinion positioned to mesh with said teeth, whereby said chair post may be moved independently of said slide and thereafter simultaneously therewith.

8. Chair elevating mechanism comprising a chair post having one section adapted to be secured to a chair and the other section swingingly mounted, a member having a slide adjacent to one end and having a lost-motion connection to said first-mentioned chair post section, said member having a second slide at the opposite end and on the opposite side thereof, and a slide for said last-mentioned slide.

9. In combination, a chair, a post having one section in supporting relation to said chair and the other section swingingly mounted on said first-mentioned section, a slide support for said first-mentioned section, said sections being provided with teeth

constituting a rack, a pinion positioned to mesh with the teeth of said rack, means for preventing a swinging movement of said second-mentioned section when said pinion engages the teeth thereof, and means for preventing the opposite swinging of said second-mentioned section when said pinion approaches one end thereof.

10. In combination, a sectional folding chair post provided with teeth constituting a rack, a guide, at least one section of said post and said guide having interlocking dovetail portions, and a second guide, the latter and said first guide having interlocking dovetail portions.

CLARENCE W. MOORE.
